MARK G. STEWART, OF SHREVEPORT, LOUISIANA, ASSIGNOR TO PELICAN WELL TOOL AND SUPPLY COMPANY, OF SHREVEPORT, LOUISIANA, A CORPORATION OF LOUISIANA

CASING SEAL FOR WELLS

Application filed June 2, 1928. Serial No. 282,451.

This invention relates to seals for well casings, particularly those used in connection with oil wells, wherein the casing consists of a plurality of substantially axially aligned sections of progressively decreasing diameters from the ground level downward, and in which it is desirable to form a seal between the adjacent ends of each pair of sections, to prevent water, gas or the like from entering the casing at the joints formed between the different sized sections.

Seals have been provided for this purpose, prior to my invention, such, for example, as a seal comprising a single relatively large and heavy lead ring applied to the upper end of the smaller casing section and adapted to be expanded, after the smaller section has been "set" into sealing contact with the inner wall of the larger section, by means of a tapered plug, mandrel or swedge being run down into the well and hammered from above to effect expansion of the ring.

Seals of this type are subject to becoming loose and to leaking, due to vibration, etc., and are extremely difficult, if not impossible, to tighten. This type of seal also leaves the relatively soft lead exposed to injury by tools which from time to time are passed into the well. Also with this type of seal it is impossible to remove the smaller casing section after the seal has been made.

Efforts have been made to overcome these objections, to some extent at least, by providing a seal comprising a hollow conical member threaded onto the upper end of the smaller casing section, and providing a large and heavy single lead ring around the conical member, with one end internally beveled to the same angle as the outside of the conical member, the opposite end of the ring being flat, for engagement with a similar flat end of a setting head, which is threaded onto a cylindrical projection on the upper end of the conical member. By screwing the setting head down on the conical member the heavy lead ring is expanded into sealing contact with the inner wall of the larger section of the casing.

While this latter construction to some extent overcomes the objections to the former

construction by protecting the lead ring, nevertheless presents difficulties, such as materially decreasing the diameter of the entrance into the smaller section of the casing, due to the reduced diameter of the upper cylindrical end of the conical member on which the setting head is threaded.

With this latter construction the setting head and conical member, are left in the well after the joint is formed, to permit tightening of the seal should occasion arise, but due to the heavy construction of the single lead ring, expansion thereof, in the manner noted, is an extremely difficult operation. Also with this construction it is impossible to remove the smaller section of the casing, should such be required, as any attempt to raise the same will merely tend to further expand the lead ring, by raising of the conical member and thereby forcing the ring into greater frictional contact with the inner wall of the larger section.

One object of my invention is to provide a casing seal in which the common single heavy lead ring is replaced by a plurality of rings of a comparatively lighter weight, and constructing the rings and the co-operating elements by which the rings are expanded in such a manner that the expansion thereof will be greatly facilitated, over the expansion of the common single heavy ring.

Another object of the invention is to construct the elements of the seal in such a manner that the lead rings will at all times be protected against injury by tools or other objects which from time to time are passed down through the well casing and in such a manner that the seal will have a through passage of a diameter at least as great as the diameter of the smaller casing section, thereby eliminating all obstructions at the entrance to the smaller section.

Another object is to provide a seal which can be tightened from time to time should the necessity arise.

Still another object of the invention is to construct the elements of the seal in a manner which will permit the smaller casing section to be removed at any time that such should be desired. The details of the con-

struction of my improved casing seal will be fully disclosed hereinafter, reference being had to the accompanying drawings, of which:

5 Fig. 1 illustrates a longitudinal sectional elevation of a pair of different sized casing sections in their relative "set" positions, and the sealing means located therein prior to its being "set".

10 Fig. 2 is a view similar to Fig. 1, but showing the sealing means in its "set" position;

Fig. 3 is a sectional plan view taken on the line 3—3 of Fig. 2; and

15 Figs. 4, 5 and 6 are sectional elevations of modified forms of the invention.

Referring to Fig. 1, 1 illustrates a casing section having been lowered and permanently "set" in the ground. 2 illustrates a casing section of smaller diameter than the section 1, having been similarly lowered and "set" in the ground. In order to form a seal between the adjacent coaxially aligned ends 3 and 4 of the respective sections 1 and 2, the end 4 of the section 2 is externally threaded as illustrated at 5, to receive internal threads 6 formed in one end of a sleeve 7. The co-operating threads 6 and 7 are tapered in accordance with standard pipe practice. The opposite end of the sleeve 7 is also provided with internal tapered threads 6a, adapted to receive external tapered threads 8 on one end 9 of a nipple 10. The opposite end 11 of the nipple 10 is provided with external non-tapered threads 12. A plain, external surface 13 is formed on the nipple 10 between the threads 8 and 12 of the respective ends 9 and 11 thereof. In this construction the nipple 10 functions as a continuation of the section 2 and the sleeve 7 functions as a shoulder on the said section 2. This construction may be replaced by the construction shown in Fig. 5, in which the section 2a is provided with a shoulder in the form of a collar 7a welded or otherwise rigidly secured to the section 2a. The section 2a has non-tapering threads 12a and a plain surface 13a corresponding to the threads 12 and surface 13 of the nipple 10.

45 A "setting" head 15 is provided with internal non-tapering threads 16 at one end 17 thereof, which are adapted to co-operate with the non-tapering threads 12 on the end 11 of the nipple 10. The opposite end 18 of the setting head 15 is provided with a plain bore 19 which is adapted to receive one end of a "setting" tool 20.

50 Around the nipple 10, intermediate the upper internally beveled end 21 of the sleeve 7 and the lower externally beveled end 22 of the setting head 15, is mounted a plain sleeve 23 which is composed of pliable sheet copper or the like, and which is split longitudinally as illustrated at 24 in Fig. 1. The split sleeve 23 has a flared end 25 which engages the externally beveled end 22 of the setting head 15.

The sleeve 23 may have a butted joint at the line 24, or the respective longitudinal edges of the sleeve may overlap as desired. The purpose of this split sleeve will be more fully disclosed hereinafter.

70 Around the split sleeve 23 is positioned a series of superposed annular elements 26, 26 composed of relatively soft lead or like material. The outer diameter of said rings is substantially equal or less than the outer diameters of the setting head 15 and the sleeve 7, in order that the relatively soft sealing material will be protected from injury by these other elements when the casing section 2 is being lowered within the section 1.

75 Each ring 26 has an internally beveled end 28 of a predetermined angle relative to the longitudinal axis of the element and an externally beveled end 27 of a greater angle, relative to the said longitudinal axis than that of the internal bevel 28.

80 The externally beveled end 27 of the lowermost sealing ring 26 is adapted to enter the internally beveled end 21 of the sleeve 7. The externally beveled end 27 of each of the 85 successively superposed rings enters the internally beveled end 28 of the adjacent ring next below. The externally beveled end 22 of the setting head 15 with the flared end 25 of the split sleeve 23 thereover, enters the internally beveled end 28 of the uppermost packing ring 26. The angle of the externally beveled end 22 of the setting head 15 is substantially the same as the angle of the externally beveled end 27 of each ring 26.

90 From the above it will be seen that each opposed pair of faces on the setting head 15 and the superposed rings 26, are differentially beveled, which facilitates the expansion of the rings 26, when the setting head 15 is moved toward the sleeve 7, by causing the internally beveled face having the lesser angle to over-ride the externally beveled face of the greater angle, thereby causing the internally beveled ends of the rings 26 to flare outwardly when initial longitudinal pressure is exerted on the rings, thus making the expansion uniform and complete throughout the entire body of the sealing material.

95 The setting tool 20 is provided with a pair of laterally extending diametrically opposite lugs 30, 30, each of which is adapted to enter a longitudinal vertically extending slot 31 formed in the non-threaded end 18 of the setting head 15.

100 Each of the slots 31 is provided with a horizontal extension slot 32 which is positioned at a right angle relative to the direction of the slot 31. Each horizontal extension slot 105 32 terminates in a socket 33, communicating with the extension slot 32, said sockets extending vertically and parallel to the entrance slots 31.

110 The setting tool 20 is further provided with a shouldered head 34 which is adapted to be 115

secured to the lower end of a lowering and sealing shaft 35. This shaft 35 is the usual or standard drill stem employed in the boring of the well, prior to the lowering of the casing thereinto.

In operation, the casing section 1 having previously been "set" in the ground, the section 2 thereof is connected to setting tool 20 secured to the end of the drill stem 35 in the manner illustrated in Fig. 1, and lugs 30 of the setting tool 20 being positioned within the sockets 33 of the setting head 15. The section 2 is then lowered to the bottom of the previously bored hole, after which the stem 35 is employed as a medium for rotating the setting head 15.

After the casing section 2 has been lowered to the bottom of the hole, continued downward movement of the drill stem 35 causes the lugs 30 to move out of the sockets 33 into the horizontal slots 32 after which the stem or shaft 35 is turned, in the present instance in a clockwise direction, until the sides of the lugs 30, 30 engage the sides 38, 38 of the entrance slots 31. Such turning of the stem 35 and setting tool 20 causes the straight or non-tapering threads 16 of the setting head 15 to move down on the straight or non-tapering threads 12 of the end 11 of the nipple 10 until the externally beveled end 22 of the setting head 15 enters the internally beveled end 28 of the uppermost sealing ring 26, the externally beveled ends of the respective sealing rings to subsequently enter the internally beveled ends of the adjacent rings, and the externally beveled end of the lowermost sealing ring to enter the internally beveled end 21 of the sleeve 7.

Continued rotation of the setting tool 20 by the stem 35 causes the setting head 15 to approach the threaded sleeve 7, and thereby longitudinally compress and radially expand the sealing rings 26, 26 into contact with the casing section 1 to form a gas and water tight seal between the end 3 of the casing section 1 and the nipple 10 attached by the sleeve 7 to the end 4 of the casing section 2, as shown in Fig. 2.

If desired, the nipple 10 and sleeve 7 may be made of one integral piece, but the construction shown is preferable for the convenience of manufacture. The sleeve 7, nipple 10 and casing section 2 are rigidly assembled prior to the lowering of the section 2 into the hole, thus no subsequent relative rotation between these elements is effected during the sealing operation.

The split sleeve 23 functions to keep the comparatively soft material, of which the sealing rings 26 is composed, from being forced into the threads 12 on the end 11 of the nipple 10 as the seal is being formed, the split 24 thereof permitting the said sleeve to spread over and adhere to the end 17 of the setting head 15, as shown at 40 in Fig. 2,

when the said setting head 15 approaches the sleeve 7.

When the seal is completed or "set", the setting tool 20 and the stem 35 are moved vertically, the lugs 30, 30, which, as above described, lie within the entrance slots 31, 31, during the seal forming operation, moving out of the entrance slots 31, 31 without fear of breaking the seal just formed, as might be the case if the horizontal slots 32, 32 extended in the opposite direction relative to the entrance slots, from that shown in the drawings and it were consequently necessary to reverse the direction of rotary motion of the said setting tool in order to remove it from the setting head 15.

The setting head 15 is permitted to remain in the well after the setting tool 20 is removed therefore, the seal may be tightened at any time after it has been permanently set by reinserting the drill stem 35 with the setting tool 20 thereon, the lugs 30 readily entering the slots 31, and by turning the stem 35 in a clockwise direction to advance the head 15 toward the shoulder 21 the expansion of the rings 26 is increased.

Obviously if left hand threads are employed on the end 11 of the nipple 10 and corresponding threads formed in the setting head 15, the direction of rotation of the setting head will be reversed from that above described when the sealing operation is being effected, in which case the direction of the horizontal slots 32 will be accordingly reversed, in order that it will not be necessary to reverse the direction of rotation of the setting head from that employed in effecting the formation of the seal, to remove the setting tool from the setting head.

Under ordinary conditions, the casing section 2 is lowered into the pre-bored hole in the manner illustrated in Fig. 1, but, if for any reason, such as binding of the casing section in the hole, it would be necessary to exert a downward pressure on the casing section a shoulder 36 formed on the head 34 of the setting tool 20 will engage the upper edge 37 of the setting head 15, thus relieving the lugs 30, 30 of any strain resulting from the exertion of such pressure on the casing section.

The upper end 18 of the setting head 15 is beveled inwardly, as illustrated at 41, and the end 11 of the nipple 10 is likewise beveled, as at 42, for the purpose of axially guiding any instrument which may be lowered into the well subsequent to the formation of the seal between the respective sections thereof. The plain bore 19 of the setting head 15 is of a diameter substantially equal to that of the interior of the nipple 10, which is substantially the same as the internal diameter of the casing section 2, and guides such instrument into the nipple and subsequently into the cas-

ing section 2, thereby protecting the ends of these elements during such insertion.

In Fig. 4, I have illustrated a modified form of setting head 15a in which the plain bore 19a thereof is of a greater diameter than the interior of the nipple 10, and an annular flange 43a is formed between the plain bore 19a and the threaded bore 16a of the said setting head, the interior diameter of the flange being substantially equal to that of the interior of the nipple 10, for the purposes above set forth.

If it is desired to withdraw the smaller section of the casing after the seal has been permanently set, this operation can be effected by reinserting the drill stem 35 with the setting tool 20 thereon into the head 15, the lugs 30 entering the entrance slots 31, after which the stem is turned until the lugs enter the extension slots 32 and subsequently the sockets 33. By applying sufficient lifting force to the stem 35, the sharp edge, formed at the juncture of the internal bevel 21 and the outside face of the sleeve 7, will act as a shear to cut through the consolidated sealing mass formed by the rings 26, permitting the section 2 to pass freely through the broken seal after the passage of the sleeve 7 therethrough. The inner wall of the larger section acts as a means for resisting the upward movement of the sealing material and thereby assists in the shearing operation.

Upon referring to Fig. 2 of the drawings, it will be noted that the sealing material 26, which is necessarily of a relatively soft or plastic nature, is completely enclosed by the elements 15, 10 and 7 of the seal which are of a substantially harder nature, thus the seal is protected against possible injury, which may result in a leaky joint between the well sections, when tools and other objects of various natures are passed down through the well.

It will also be noted that the opening extending completely through the seal is at least as great in diameter as the internal diameter of the smaller section 2 of the casing, thereby eliminating all obstructions at the entrance of the said smaller casing section.

Obviously the plurality of expandible rings 26 may be replaced by a single ring having an upper internally beveled face co-operating with the externally beveled face of the setting head 15 and its lower end externally beveled to co-operate with the internally beveled face 21 of the sleeve 7, the opposed face being differentially beveled as above noted.

Fig. 6 illustrates alternate rings 26a as being respectively provided with a pair of oppositely disposed externally beveled faces 27a, 27a, and oppositely disposed internally beveled faces 28a, 28a. Expansion of the rings 26a is effected in the same manner as above noted, the internal bevels overriding

the adjacent external bevels of adjacent rings.

I claim:

A seal, for well casings, comprising a plurality of rings of plastic substance adapted to be placed in superposed relation to each other between the adjacent walls of two telescoping sections of a well casing, each ring having one end internally beveled to a predetermined angle and its opposite end externally beveled to a predetermined angle relatively less acute than the angle of the internally beveled end, the internally beveled end of one ring resting against the externally beveled end of the next adjacent ring, providing a space between said beveled faces, said rings being adapted to be compressed longitudinally, whereby the wedge action of the externally beveled ends acting within to flare the internally beveled ends progressively from the thin weak edge thereby commencing and facilitating uniform radial flowing of the plastic rings into a homogeneous plastic mass completely filling, adapting itself to, and sealing the spaces between the said adjacent walls of the said telescoping sections of the well casing.

MARK G. STEWART.
